HARRY N. WEIR, OF HOOSICK FALLS, NEW YORK, ASSIGNOR TO THE NOBLE & WOOD MACHINE CO., OF HOOSICK FALLS, NEW YORK, A CORPORATION OF NEW YORK

PAPER-MAKING MACHINERY

Application filed June 10, 1929. Serial No. 369,774.

My invention relates to improvements in Jordans, beaters and the like, used in the paper making industry, and particularly to improvements in the wood fillers employed 5 between the bars of a Jordan plug or beater roll.

Considerable difficulty is experienced, particularly with Jordan plugs, in maintaining the wood fillers between the bars especially 10 at the small end of the plug. Here, the greatest wear occurs, and the present type of fillers soon become so washed and softened that they rise up and are destroyed. Furthermore, as at present arranged, the fillers are 15 easily splintered, and particularly where a "hard stock" (stock containing a considerable quantity of foreign material such as wire, paper clips, small particles of metal etc.) is being treated, it is difficult if not impossible to maintain even the highest quality 20 of wood filler for any appreciable length of time.

Heretofore, these fillers have been arranged with the grain of the wood running 25 substantially parallel to the surface of the roll or plug. The fillers are ordinarily driven into the spaces between the bars, from the top, and secured either by being wedge-shaped in cross section, by bands, by swelling 30 into openings in sides of the bars or by a combination of these means.

I find by using fillers in which the grain of the wood runs substantially normal instead of parallel to the surface of the plug 35 or roll, so that the ends instead of the sides of the fibers are exposed, that the life of the filler is prolonged indefinitely. Moreover, this arrangement of the grain in the fillers readily lends itself to a novel and 40 greatly improved method or means for securing the fillers in place.

My invention therefore includes the novel elements and the combination and arrangement of elements described below and illustrated in the accompanying drawing in which—

The figure is a fragmentary perspective section of a Jordan plug or beater roll.

Referring to the drawing, 1 represents the 50 cast plug provided with the peripherally

spaced, dove-tail slots, 2, into which the bars, 3, are fitted. Between the main slots, 2, are smaller slots, 4, into which the wedges, 5, extending longitudinally of the plug, are inserted. The outer or upper edges, 6, of the 55 wedges, 5, are sharp and serve to split and spread the filler blocks as will be later explained. It is to be understood, of course, that the bars, 3, need not be dovetailed into the plug but may, if desired, be secured by 60 other means. Furthermore, while the slots, 4, are shown as dovetailed it may be preferable to have them formed with parallel sides.

The opposite sides of each bar, within the 65 zone to be covered by the wood fillers, are provided with projections, 7. These projections preferably merge gradually into the bars at the top, 8, so that the fillers may be driven down radially between the bars, but 70 at the bottom, 9, they form a rather sharp or abrupt offset or "barb" which prevents the filler from rising once it has been driven home.

The wood fillers, 10, it will be noted, are ar- 75 ranged with the grain, 11, running substan- tially normal to the plug so that the surface, 12, exposed between the bars is the end grain or cross grain of the wood. As the filler is driven in radially it is compressed, as shown 80 at 13, in passing the projection, 7. When it reaches the wedge, 5, the sharp upper edge of the wedge penetrates the wood and spreads or expands the bottom of the filler into contact 85 with the sides of the bars, thus effectually preventing its rising.

While it is far preferable to use my type of filler with the end or cross grain exposed at the surface, it is clear that the other features 90 of my invention, such as the wedges, 5, and the projections, 7, may be used with a filler in which the grain of the wood is disposed parallel to the surface of the plug or roll. Hence, it is to be understood that I am not 95 limited to any individual detail and that changes, within the purview of the appended claims, may be made without departing from the true scope and spirit of my invention in its broader aspects.

What I claim is—

1. A paper making machine of the character described comprising a rotating element having a plurality of cutting bars mounted thereon, and wood fillers between said bars characterized by having the grain thereof running substantially normal to the surface of the element.
2. A Jordan plug comprising a rotating element, a plurality of radially extending cutting elements mounted in said rotating element, wood fillers located between adjacent elements and characterized by having the grain thereof running substantially normal to the surface of the rotating element, means for securing said wood fillers in position, and wedges adapted to penetrate and expand the bottoms of the wood fillers located between said elements.
3. A paper making machine of the character described comprising a rotating element having a plurality of cutting bars mounted thereon, and wood fillers between said bars characterized by having the grain thereof running substantially normal to the surface of the element, and means for maintaining said wood fillers in position between said bars.
